UNITED STATES PATENT OFFICE.

JOSEPH WYBAUW, OF BRUSSELS, BELGIUM.

GAS-METER REGISTERING SEPARATELY THE CONSUMPTION BY NIGHT AND BY DAY.

SPECIFICATION forming part of Letters Patent No. 363,937, dated May 31, 1887.

Application filed September 20, 1886. Serial No. 214,052. (No model.) Patented in Belgium January 23, 1885, No. 67,633, June 17, 1885, No. 69,310, and August 7, 1885, No. 69,848; in France February 10, 1885, No. 166,960; in Germany May 4, 1885, No. 35,274, and in England May 6, 1885, No. 5,564.

To all whom it may concern:

Be it known that I, JOSEPH WYBAUW, a subject of the King of Belgium, residing at Brussels, in the Kingdom of Belgium, have invented certain new and useful Improvements in Gas-Meters for Registering Separately the Consumption of Gas by Night and by Day, (for which I have obtained patents in Belgium January 23, 1885, No. 67,633, June 17, 1885, No. 69,310, and August 7, 1885, No. 69,848; in France, February 10, 1885, April 1, 1885, and October 19, 1885, No. 166,960; in Germany, May 4, 1885, No. 35,274, and in England, May 6, 1885, No. 5,564,) of which the following is a specification.

In order that my invention may be fully understood, I will proceed to describe it with reference to the accompanying drawings, in which—

20 Figure 1 is a side elevation of that portion of a meter to which my invention in its preferred form is applied. Fig. 2 is an elevation in detail, showing a modification in which means for coupling the primary dial-wheels instead of the shafts are shown. Fig. 3 is an elevation in detail, showing another modification, in which the primary dial-wheels are coupled by means of an endless screw shaft. Fig. 4 is an elevation in detail, showing another modification, in which the coupling shown in the first modification is operated by means of a cam-dial connected to suitable clock-work. Fig. 5 is an elevation in detail, showing a modification in the form of weighted lever. Fig. 35 1^a is a detail of the bell-supporting device, showing the position it assumes when thrown out. Fig. 1^b is a detail of the same showing the device in operative position. Fig. 1^c is a detail of the same showing the device in normal or inoperative position.

The gas-meter hereinafter described has for its object the registering of the amount of gas consumed during the day and the night, respectively, the mechanism being actuated by means of variations in the gas-pressure exercised by the gas-works itself.

To this end the ordinary gas-meter is provided with a second dial, E, placed above the ordinary dial, D. The latter indicates the to-

tal consumption, while the upper dial indicates the day or night consumption. The vertical shaft F, which gives motion to this upper dial, is placed in connection with the prolongation g of shaft G of the lower dial, and may be connected to this shaft by means of a connecting coupling or muff, H. This latter carries a pin, I, which, when coming in contact with cross-bar or pusher K, is urged forward by it, and accordingly the two dials are set to motion together.

The connecting coupling or muff is lifted or lowered by means of a lever, C, pivoted at L. This lever extends to the back part of the meter, where it supports a bell, A, plunging in glycerine or mercury contained in a reservoir affixed to the meter. The interior of the bell communicates with an inlet-pipe for the gas by means of a small pipe, B. The whole attachment is protected by a cover, preventing access thereto from outside.

The working of the apparatus is as follows: When the gas-works gives the evening pressure, the bell A is raised, the coupling or muff H is lowered, the pin I comes in the horizontal plane of the cross-bar or pusher K, and when the gas entering the meter imparts to the shaft G a rotary motion with the dial D the shaft F turns similarly and the dial indices of the dial E are set in motion. The pressure being lowered, the bell descends, the shafts are disconnected, and the dial E remains stationary, while the motion of D is continued. The high pressure being generally produced at night, the evening consumption is registered on the upper dial. By subtracting the number from the total registered upon the dial D the consumption made under the low pressure is obtained; but as according to the consumption the pressure of gas may in certain cases be lowered enough to prevent the bell from being kept up the whole evening, a pawl, R, is provided, the purpose of which is to prevent the bell from being lowered before the requisite moment. This pawl may be constructed in several ways. The drawings show a pawl intended to prevent this lowering during the whole night. When the evening pressure is set, the bell rises until it strikes the weight P

on a lever, N, having supporting-arm K and pivoted at M. The pawl R falls below the tooth *r*, and the bell is so prevented from descending. In the morning the gas-works 5 gives a higher pressure during one moment, so as to lift the bell with the weight P. The heel *m* pushes against the short arm of the pawl R and throws out the long arm upon the wall of the reservoir. The pressure be- 10 ing immediately lowered, the bell falls down, the click *n* strikes the short arm, and the pawl falling, its long arm comes to normal position over the tooth *r*. It remains in this position until, the bell being lifted again in the evening 15 by the pressure, that arm falls again below the tooth *r* until morning, and so on. Another dis- position of the pawl is shown in Fig. 5. The bell being lifted, the weight P takes a vertical 20 position, with its supporting-lever N', having short arm N'', bearing on the bell. The lever bears against a stop, *k'*, and exercises no weight upon the bell. In order that the bell could be lowered, it is necessary that the pressure should decrease more or less, and this gen- 25 erally happens about midnight at the moment the pressure in town is lowered. The connection of the two dials could also be obtained without any bell by the subscriber himself by means of a key; but in this case the motion 30 should be shown outside by means of a manom- eter, or a pipe being filled with gas and afford- ing control. The meter could also be provided with two exit-pipes—one for the heating-gas and the other for lighting purposes. This lat- 35 ter is provided with a cock, the opening or shutting of which causes the connection or dis- connection of both dials. The subscriber can- not thus use the gas for lighting purposes un- less the two dials are connected.

40 The bell may be replaced by a membrane or a flexible partition. The connecting coupling or muff may be replaced by any of the dispositions shown, Figs. 2 and 4, where an auxiliary wheel, H', mounted on a lever, C', con- 45 nects with both primary dial-wheels O Q at the moment the point *e* is lowered by the lever C. The principal dial may also be dispensed with and the endless screw H', Fig. 3, be main- 50 tained, which gears with one or both the pri- mary wheels of the dials—one for the day and the other for the night consumption of gas. The upper primary dial-wheel is supported 55 on the short arm of a lever, C'. Finally, the connection may be obtained by means of a clock-work. The shaft S, Fig. 4, of the clock, making one revolution in twenty-four hours, carries an eccentric or cam dial, coming in contact with a screw, *e*, on the long arm of the lever L. As the eccentric comes in contact 60 with the end of screw *e* by its side of longest radius, the auxiliary wheel H' does not connect with the lower dial-wheel. When the shortest radius side of the eccentric is in front of screw *e*, the arm L rests on the stop Z and

the end of the screw does not touch the eccen- 65 tric. Both dials are then connected. The time of connection varies according to the shape of the eccentric. This latter marks one division in twenty-four hours. It is fixed by a screw on the conical end of the shaft. This 70 arrangement permits of easily adjusting the working of the apparatus.

Having thus described my invention and in what manner the same has to be carried out, what I claim is—

75

1. The combination, with a gas-meter hav- 80 ing a mechanism for registering the total con- sumption of gas, of a mechanism for register- ing a part of the consumption of gas, and means for connecting the mechanisms, sub- stantially as described.

2. The combination, with a gas-meter hav- 85 ing a mechanism for registering the total con- sumption of gas, of a mechanism for register- ing the amount of gas consumed at certain times operated by the shaft of the first-named mechanism, substantially as described.

3. The combination, with a gas meter hav- 90 ing a mechanism for registering the total con- sumption of gas, of a second mechanism for register- ing the amount of gas consumed at certain times, a coupling for connecting the shafts of the mechanisms, and a lever for shift- ing the coupling, substantially as described.

4. The combination, with a gas-meter hav- 95 ing a mechanism for registering the total con- sumption of gas, of a second mechanism for register- ing the amount of gas consumed at certain times, and means for automatically 100 connecting the mechanisms by gas-pressure, substantially as described.

5. The combination, with a gas meter hav- 105 ing a mechanism for registering the total con- sumption of gas, of a second mechanism for register- ing the amount of gas consumed at certain times, and means for automatically dis- connecting the mechanisms by gas-pressure, substantially as described.

6. The combination, with the main dial- 110 shaft G, of the second dial shaft F, coupling or muff H, lever C, and bell A, substantially as described.

7. The combination of the lever C, bell A, having tooth *r*, heel *m*, and click *n*, and the pawl R, substantially as described.

115

8. The combination of the bell A, means for sustaining the bell, and the weighted lever P N, having supporting-arm *k*, substantially as described.

9. The combination, with the main dial 120 mechanism and the second dial mechanism, of the coupling and means for automatically operating the coupling by the gas-pressure, sub- stantially as described.

J. WYBAUW.
